UNITED STATES PATENT OFFICE.

FRED A. VOELKE, OF TIPTON, INDIANA.

HOLLOW METALLIC BODY.

No. 795,870.

Specification of Letters Patent.

Patented Aug. 1, 1905.

Application filed January 20, 1904. Serial No. 189,855.

To all whom it may concern:

Be it known that I, FRED A. VOELKE, a citizen of the United States, and a resident of Tipton, in the county of Tipton and State of Indiana, have invented certain new and useful Improvements in Closed Hollow Metallic Bodies, of which the following is a specification.

This invention relates to closed hollow metallic bodies, and has for its object to produce bodies of the character described that are comprised of a plurality of seamless integral layers, of which each has the form of the article and all together constitute a single shell.

The articles herein described and claimed are those which are produced by the process set forth and described in another application that will be filed at or about the time when this application is filed.

The inventions herein set forth and claimed also include means for strengthening such articles of the kind described as are required to withstand either compression from without or stresses applied from within which are calculated to burst the article and also include internal braces for such articles.

The process which forms the subject-matter of the other application referred to describes the construction of hollow articles which are seamless and yet completely closed and which are built up with a plurality of seamless metallic laminæ each of which has the form of the integral article. Said application, furthermore, describes a process by which the laminæ are disposed one upon another and so united that they constitute a single shell.

Referring to the drawings filed herewith, Figure 1 shows in perspective an article of the kind described which is adapted for use as a float. Fig. 2 shows a cross-section on the line 2 2 of Fig. 1. Fig. 3 shows a cross-section on the line 3 3 of Fig. 2. Fig. 4 shows the brace employed in the float shown in the figures just referred to. Fig. 5 represents, partially in section, a vessel adapted to resist bursting stresses; and Fig. 6 is a section on the line 6 6 of Fig. 5.

The said application for the process by which articles of this nature are constructed sets forth *seriatim* the construction of a core of some fusible material having the outer form which it is desired the article shall have, the deposit electrolytically of a metallic surface upon said core, the expulsion of the core from the shell so constructed, and the building up of this united shell into a shell of the desired thickness by dipping the shell into a bath of

suitable molten metal or its alloy and subjecting it to an electrolytic bath. In the said application for a patent for the process it also describes the way in which the strengthening-pieces and the braces are embedded in position within the core so that they will be in proper position within the shell when the latter is formed and so the electroplating will cover said parts also, thereby securing them in place within the shell. In the said application for a patent on the process attention is also drawn to the fact that the several layers of the articles formed as aforesaid by electrolytic deposition and dipping in molten metal of the character therein described builds up a shell in which the different laminæ or layers so formed are knit together, so as to constitute a single integral shell, by reason of the fusion of the metals of adjacent layers. In the said application for a patent on the process it is also shown how closed hollow seamless articles like those described in said application can be made in various and many forms, according to the requirements of the use to which they are to be put, and how they may be varied in thickness of shell and in the manner of strengthening and bracing.

The float represented in Figs. 1, 2, and 3 has a shell comprising three seamless integral layers, each of which has the form of the article. These are respectively the inner shell 1, formed by deposit in an electrolytic bath, the next outer shell 2, formed upon the first shell 1 by dipping it into a suitable bath of molten metal or its alloy, and the outer layer 3, formed like the first by electrolysis. Each one of these three layers is seamless and integral and has the form of the article. The layer 2 is blended with the layer 1 during the process of dipping the shell, when it consists of the inner layer 1, into the molten metal, so that the shell constituted of layers 1 and 2 is practically one integral shell. Upon this shell the outer layer 3 is deposited by electrolysis, and, as in every case where a metal is deposited electrically, the layer 3 thus deposited adheres to and unites closely with the surface of the layer 2 upon which the deposit is made.

The article shown in the first three figures represents one that must withstand compression, and is accordingly provided with strengthening-pieces 4 and 5 and a brace that extends across the interior of said articles from one of said strengthening-pieces to the other. The strengthening-pieces are repre-

sented as consisting of plates whose outer surfaces have the general contour of that part of the surface of the article that is to be made beneath which they are intended to be placed—that is to say, in the article shown in Figs. 1 and 2 the upper surface of the strengthening-pieces is round. The plates 4 and 5 are represented as perforated at their center to receive, respectively, the ends of the brace 6. Said plates are represented in the drawings as placed diametrically opposite to each other and as screwed upon the ends 7 and 8, respectively, of the brace. One of the plates 4 is represented as having a neck 9, and all three of the layers 1, 2, and 3 are formed upon this neck and are respectively integral with the surface of the article itself. The neck 9 is represented as threaded internally at 10 in order that it may be attached to the apparatus with which it is to be used.

When one of the strengthening-plates, as 4, is made with a neck, as shown in Figs. 1 and 2, the position of the neck within layers of the shell tends to retain the strengthening-pieces and their braces in proper position within the article; but in addition to this the plates are held in place by the connection between the plates and the inner electrolytic deposit 1, for, as stated above, said deposit is made directly upon said plates.

Fig. 3 shows a brace which may be used, if desired, in addition to the strengthening-plates and brace described. This brace consists of a ring 11, hub 13, and radial arms 12, connecting said ring with the hub. There is a central perforation 14 in the hub, adapted to receive the brace 6. This transverse brace is screwed upon the brace at any desired point and in any suitable manner. In the drawings it is represented as attached to the brace 6 midway of its length.

An oblong figure is shown in Fig. 5 whose shell is comprised of a plurality of seamless integral laminae or layers of the character described with reference to the float shown in Figs. 1 and 2 and which is also represented as provided with strengthening pieces or plates 17 and as having a diametrical brace 18, like those described above; but in addition thereto the oblong article shown in Fig. 5 is represented as constructed without a neck for attachment and as strengthened to resist bursting stresses. The plate 17, and, if desired, a similar plate at the other end, (not shown,) is attached to the diametrical brace 18 in any suitable manner. In the drawings it is represented as screwed upon the threaded end 19 of said brace. The electrolytic lamina or layer 15 is deposited upon the plate 17 in the manner described above with reference to the float shown in Fig. 2. An additional strengthening-piece 20 is then attached to the end of the brace 18 in some suitable manner, as by being screwed upon the threaded end 19 of said brace, and is adapted to fit snugly

upon the electrolytic layer 15. The brace 18 is represented as bored longitudinally and then transversely, so as to make a passage into the article for the purpose of subjecting the core to compressed air while it is being formed and for the further purpose of removing the core from the electrolytic layer 15, when the latter has been deposited, in accordance with the process described in the other application. The bore is closed by a plug 21. The outer surface of the plate 20 has the proper contour for the end of the article that is to be constructed. When the strengthening-pieces 20 have been placed upon the respective ends of the article as before described, the outer coating 16 is formed thereon by dipping it into a bath of molten metal of the character described above, so that an integral seamless layer is formed over the electrolytic layer 15, and the outer plates 20, constituting, with the layer 15, one integral seamless shell, as described above. Fig. 5 also represents two transverse braces which are similar to the transverse braces shown in connection with Fig. 2 and which consist, respectively, of a hub 22, having a perforation adapted to receive the brace 18, the ring 23, conforming to the inner face of the layer 15, and radial arms 24, connecting said ring and said hub. These transverse braces may be located at any desired points upon the brace 18 and are secured thereto in any suitable manner.

It is obvious with respect to the article shown in Fig. 5, as well as that shown in Figs. 1 and 2, that the shell may be built up by electrolytic deposit and dipping to any desired thickness. It is also obvious that when the article is braced against bursting stresses the shell may be built up in the same way to any desired thickness both before and after the strengthening-pieces 20 or similar pieces are put in place. Furthermore, it is clear that the strengthening-pieces and braces may be placed in articles of the kind described of many forms or shapes and may be located at any desired points therein and yet be within the scope of this invention, whose essence is that the article, whether or not it is strengthened or braced, shall be a hollow closed metallic body and whose shell shall consist of a plurality of layers or laminae each of which is seamless and has the form of the article and all of which together are so united or connected that they constitute a single integral shell that answers the above requirements.

What I claim is—

1. An article of manufacture consisting of a closed, seamless, metallic shell, and a transverse brace contained wholly within said shell, and extending across its interior between two points on its inner surface, and attached to said shell by the deposit of the metal of the shell upon the ends of said brace.

2. An article of manufacture consisting of a hollow, closed, metallic body, comprising a plurality of seamless, integral layers, each having the form of the body, and together constituting a single shell, and a strengthening-piece interposed between two of said layers.

3. An article of manufacture consisting of a hollow, closed, metallic body, comprising a plurality of seamless, integral layers, each having the form of the body, and together constituting a single shell, a strengthening-piece interposed between two of said layers, and a strengthening-piece conforming to the inner face of the article upon which the innermost layer is directly deposited.

4. An article of manufacture consisting of a closed, hollow, metallic body comprising a plurality of seamless layers, each having the form of the body, and collectively constituting a single shell, and a strengthening-piece interposed between two of said layers, upon which piece one of said last-mentioned layers is directly deposited.

5. An article of manufacture consisting of a closed, hollow, metallic body comprising a plurality of seamless layers, each having the form of the body, and consisting of electrolytic deposits, and a deposit formed by dipping in a molten metal or its alloy, and collectively constituting a single shell, and a strengthening-piece interposed between two of said layers, upon which piece the outer of said last-mentioned layers is directly deposited.

6. An article of manufacture consisting of a closed, metallic shell formed by deposition of the metal upon a form, and one or more strengthening-pieces conforming to the inner face of the article, upon the outer surface of which the metal of the shell is directly deposited, and to which it is thereby united.

7. An article of manufacture consisting of a closed, metallic shell formed by deposition of the metal upon a form, metallic strengthening-pieces conforming to the inner face of the shell, upon the outer surface of which said shell is directly deposited and to which it is thereby united, and a transverse brace connecting said pieces.

8. An article of manufacture consisting of a closed, hollow body comprising a plurality of seamless layers, each having the form of the body and consisting of electrolytic deposits, and deposits formed by dipping in a molten metal or its alloy, and collectively constituting a single shell, a strengthening-piece conforming to the outline of the article upon which the innermost of said layers is directly deposited, and a strengthening-piece interposed between two of said layers upon which piece the innermost of said last-mentioned layers is directly deposited.

9. An article of manufacture consisting of a closed, hollow body comprising a plurality

of seamless layers, each having the form of the body and consisting of electrolytic deposits and deposits formed by dipping in a molten metal or its alloy, and collectively constituting a single shell, a strengthening-piece interposed between two of said layers upon which piece the center of said last-mentioned layers is directly deposited, other strengthening-pieces upon which the innermost of the layers is directly deposited, and a transverse brace connecting said last-mentioned strengthening-pieces.

10. An article of manufacture a float comprising a hollow member, a longitudinal brace, being of a length substantially commensurate with the internal diameter of said hollow member, diametrically disposed therein, and end plates being mounted upon the extremities of each brace and provided with rotund surfaces fitting said hollow member internally, and united thereto.

11. An article of manufacture, a float comprising a hollow shell of a general rotund form, a longitudinal brace of a general tubular form, said brace being disposed diametrically within said hollow shell and threaded at its extremities, said longitudinal brace being of a length substantially commensurate with the internal diameter of said hollow member, and end plates screwed upon said extremities and provided with convex faces fitting said hollow shell internally.

12. An article of manufacture, a float comprising a seamless hollow member, a longitudinal brace of tubular form disposed diametrically within said hollow member and provided with threaded ends, said longitudinal brace having a length commensurate with the internal diameter of said hollow member, and end plates screwed upon said threaded end and provided with surfaces bounded by the internal surface of said hollow member.

13. An article of manufacture, a float comprising a seamless, rotund, hollow member provided integrally with a neck, a pair of end plates disposed within said hollow member and provided with convex surfaces for engaging the same internally, one of said end plates being provided with a neck disposed concentrically to said neck of said hollow member, and a longitudinal brace connecting said end plates together, one end of said tubular brace abutting the integral surface of said hollow member.

14. An article of manufacture, a float consisting of a closed, seamless, hollow, metallic shell, having a neck integral therewith for purposes of attachment, the whole article, including its neck, constituting an even, continuous, seamless surface.

15. An article of manufacture, a float consisting of a closed, seamless, hollow body, having a neck for purposes of attachment, said body and neck comprising a plurality of superimposed, integral, seamless metallic layers,

each having the form of the body and neck, and together constituting a single shell.

16. An article of manufacture consisting of a closed, seamless, metallic shell, a transverse brace contained within said shell and attached to the sides of said shell, and a second brace, supported by the brace first mentioned and at right angles thereto that engages the inner surface of said shell.

17. An article of manufacture consisting of

a closed, seamless, metallic shell, a transverse brace contained within said shell and attached to the sides of said shell, and a ring-shaped brace supported by the brace first mentioned, at right angles thereto, that engages the inner circumference of said shell.

FRED A. VOELKE.
